Primary Examiner — Stella Reid*Assistant Examiner* — Carissa C Fitts(74) *Attorney, Agent, or Firm* — Sughrue Mion, PLLC(57) **CLAIM**

The ornamental design for a video laryngoscope, as shown and described.

DESCRIPTION

FIG. 1 is a perspective view of the front, top and right side of a video laryngoscope showing my new design;

FIG. 2 is a perspective view of the rear, bottom and left side thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom view thereof; and,

FIG. 9 is a top plan reference view of the display being opened thereof.

The elements shown in broken lines are for illustrative purposes only and form no part of the claimed design.
